YARN DELIVERY GUIDE MEANS

Pacific J. Thomas, Wyoming, Pa., assignor to U. S.
 Textile Machine Company, Scranton, Pa., a
 corporation of Pennsylvania

Application June 17, 1949, Serial No. 99,719

10 Claims. (Cl. 242—43)

1

This invention relates to reciprocable yarn delivery guide means for textile machines of the yarn winding and twisting type adapted to provide so-called "headless" yarn packages having tapered or inclined end construction.

The well known reciprocable yarn delivery guide devices heretofore provided for textile machines of the type indicated, are operated in unison, but each such device is arranged to serve a separate machine section. Each device is provided with a free yarn delivery end that can be manually moved, or swung, by the machine operator, from its operative or yarn delivery position, to an inoperative position. The devices are unitedly operated by means arranged to constantly reciprocate the yarn delivery end of each device, back and forth across the particular yarn receiving spool which it serves, while the machine is in operation, and when a particular device is swung to its inoperative position while the machine is in operation, the yarn guide element at the free end thereof will not come to a complete standstill, but will continue to reciprocate to a certain extent. When the yarn breaks, or the bobbin being wound is filled, in a particular machine section served by such a device, the operator moves the device to its inoperative position, without shutting down the machine, and then performs the necessary spool changing and yarn rethreading operations. Since the device constantly reciprocates, even after the device is swung to its inoperative position, the machine operator experiences more or less difficulty in placing the yarn into the yarn guide element of the device, particularly when the machine is operating at high speed.

One object of my invention is to provide novel yarn delivery guide means for textile machines of the type indicated, which means overcomes the mentioned and other difficulties.

Another object is to provide such means having certain structural and functional features of advantage over the similar means of the prior art.

An additional object is to provide such means which is relatively inexpensive, as well as simple in construction and operation.

It is also an object to provide such means in the form of a unit which can be readily embodied in a textile apparatus of the type indicated, so as to form a standard or conventional part thereof, or which can be supplied as an attachment for such an apparatus to replace the similar means originally incorporated in the apparatus.

Another object is to provide a textile apparatus

of the type indicated, having in combination with a yarn receiving bobbin, means for rotating the bobbin, and a reciprocating yarn delivery device provided with a yarn guide aperture, which device is mounted so as to be movable, or swingable, during operation of the apparatus, from an active location of reciprocation where the yarn guide aperture is in yarn feeding position adjacent said bobbin, to an inactive location of reciprocation where the yarn guide aperture is in rethreading position; of means arranged to maintain the yarn guide aperture of said device on the center line dividing the reciprocating stroke length of the device while the latter is in its inactive location of reciprocation.

A further object is to combine with the parts of a textile apparatus recited in the previous paragraph, of means including a novel cam element, or plate, which can be selectively mounted in various stationary positions, so as to either maintain the yarn guide aperture of the yarn delivery device in fixed location while the latter is in its inactive position of reciprocation, or to cause limited movement of the yarn guide aperture of the yarn delivery device along the center line dividing the reciprocating stroke length of the device, while the latter is in its inactive location of reciprocation.

With these and other objects in view, which will become more apparent from the following detailed description of one practical and illustrative form of my yarn delivery guide means for textile machines shown in the accompanying drawings, the invention comprises the novel elements, features of construction and arrangement of parts in cooperative relationship, as more particularly indicated by the hereto appended claims.

In the accompanying drawings:

Figure 1 is a partial vertical sectional view of one of the machine sections of a yarn winding and twisting apparatus of the type indicated, and shows one form of my invention applied thereto.

Fig. 2 is an enlarged top plan view of some of the parts illustrated in Fig. 1, and shows certain of said parts in various positions, as indicated by dot-and-dash lines.

The novel yarn or strand delivery guide means of my invention is particularly designed to facilitate the rethreading work of a machine operator, when it becomes necessary for him to substitute an empty spool or bobbin for the one which has been filled in a particular machine section, or when the yarn or strand being wound onto a spool of such a machine section breaks during the winding operation.

As the description proceeds, it will become apparent that my invention accomplishes this purpose by simple means, which, under the conditions mentioned, is arranged to maintain the yarn delivery guide element to be rethreaded, at a certain inactive location during continued operation of the machine. Furthermore, that the said location substantially coincides with the location of the pivot point of movement carried out by the yarn guide arm, or finger, which carries the guide element, so that the yarn receiving aperture of the guide element is virtually maintained at a standstill and can, therefore, be rethreaded without difficulty or loss of time.

Fig. 1 of the drawings generally discloses certain parts of a modern high speed winding and twisting machine having my invention applied thereto.

The usual and well known parts of one of the plurality of similar aligned sections of such a machine generally comprise a yarn supply spool 1, arranged to feed a yarn Y through a fixed wire eyelet guide 2, over a stationary guide rod 3, to a pivotally mounted yarn guide device 4, the upper or outer free end of which is provided with a standard yarn delivery element 4^a, arranged to deliver the yarn Y directly to a yarn receiving spool 5, driven by a drum 6, that is secured to a longitudinally extending power operated shaft 7, which rotates all the drums of the aligned machine sections in the direction indicated by the arrow in Fig. 1. The yarn delivery element 4^a is usually provided with an inclined yarn guide E and has a yarn delivery point 4^c. The yarn receiving spool 5 is detachably mounted for free rotation and replacement in the upper end of a yoke 8, and the lower end of the latter is pivotally supported, all in accordance with the usual practice. A tension spring 9 has one end secured to the yoke 8, as shown, and the other end fixedly anchored, so as to urge the yoke 8 toward the drum 6 and thereby maintain the yarn receiving spool 5 yieldingly in contact with the driving drum 6, during the yarn winding action.

Also extending longitudinally of the machine along all the aligned sections thereof, is a fixed rail or bar 10 and an axially reciprocated traverse rail 11, that is operated in usual and well-known manner by power actuated means of the machine. The parts so far described are the standard or conventional parts of a yarn winding and twisting machine of the type indicated.

The yarn delivery guide devices 4 of the prior art, are usually operated by means causing the upper or outer free yarn delivery elements 4^a thereof to be moved laterally, back and forth across the respective yarn receiving spools 5, so as to effect laying of the yarn thereon to build up so-called "headless" yarn packages, having either straight or tapered ends. When the yarn breaks, or the spool 5 is filled, the yarn delivery element 4^a of such a prior art device can be manually moved, or swung, by the machine operator, from its operative position A, indicated in full lines in Fig. 1, to its inoperative position B, indicated in dot-and-dash lines in said figure. Due to the fact that such a prior art device 4 is supported, in one way or another, on the traverse rail 11, and the latter continues to reciprocate axially, after the element 4^a is swung to its said inoperative position B, the element 4^a also continues to reciprocate laterally, back and forth, to a greater or lesser extent, depending upon the

cam or other means provided in such prior art arrangements for effecting actuation of the yarn delivery guide element 4^a. This sidewise motion of the element 4^a, makes it difficult for the machine operator to rethread the latter, particularly when the machine is operating at high speed, and more or less time is lost by the operator in the performance of this task.

To eliminate this difficulty and avoid the time loss resulting therefrom, I provide novel means adapted to effect operation of the yarn delivery element 4^a, as usual, when the latter is in its operative position A. However, when the element 4^a is swung to its inoperative position B, the said novel means will function to locate and maintain the element 4^a at a position such that the machine operator can quickly and easily rethread the element 4^a, without difficulty and loss of time.

The novel means provided for this purpose in accordance with my invention, generally comprises a plate 12, which is adjustably secured in fixed position on the rail 10 by two bolts 13 and 14, and provided with a cam slot 15, having cooperatively mounted therein for movement therealong, a cam roller 16, secured to the lower depending portion of a laterally swingable bracket element 17, mounted for turning movement on a shouldered pivot stud 18, secured to a stationary bracket plate 19. The entire assembly comprising parts 16, 17, 18, and 19, is secured in fixed relation to the machine traverse rail 11 by suitable means, such as by machine screws 20.

The plate 12 is arranged so that its angular position on the rail 10 may be varied to effect adjustment of the cam slot 15 thereof and thereby selectively determine the yarn laying movement of the yarn delivery element 4^a. For this purpose the plate 12 is provided with an arcuate adjustment guide slot 21, through which passes the shank of the bolt 14. By first slightly loosening the bolts 13 and 14, the plate 12 can be angularly adjusted about the pivot bolt 13, within the limits of the slot 21. The bolts 13 and 14 are then tightened to fix the plate 12 in its adjusted position on the fixed rail 10.

Mounted on the swingable bracket element 17 is a conventional yarn guide arm 4^b, having the standard yarn delivery element 4^a mounted thereon at its outer free end. The opposite or lower end of the arm 4^b terminates in a tubular construction, within which is pressed, or suitably held in some other manner, a bushing 22. The guide arm 4^b, element 4^a, and bushing 22, are arranged to limitedly rotate, or swing, about the shank of an elongated mounting screw 23, secured in fixed position between two tabs 24 and 25 integrally formed on the swingable bracket 17. The tabs 24 and 25 are so arranged as to prevent the yarn guide arm assembly from shifting in axial direction along the mounting screw 23 while the yarn delivery point 4^c of the element 4^a carries out its arcuate yarn laying movement adjacent to the yarn receiving tube or bobbin 5, as determined by travel of the roller 16, in cam slot 15, of the plate 12, during reciprocal actuation of the traverse rail 11.

Operation

In operation, the empty tube or bobbin 5, on which the yarn, or strand Y, is to be wound, is rotated by frictional contact with the driving drum 6. When the yarn delivery guide element 4^a is properly threaded, as shown in Fig. 1, the yarn passes over the inner portion of the element

4^a, through the yarn guide eye E, and under the outer portion of the element 4^a, so that when the yarn Y leaves the element 4^a at the yarn feeding or delivery point 4^c and becomes tensioned, the yarn Y will hold the element 4^a suspended from contact with the yarn package being wound.

At the beginning of the yarn winding operation, the guide arm 4^b is vertically inclined toward the tube 5, in determined relation with respect to the pivot screw 23. As the traverse bar 11 reciprocates or oscillates in axial direction, back and forth, to carry out its determined stroke, the cam roller 16 moves along the cam slot 15, thereby causing the swingable bracket 17 to move about pivot 18, an effecting oscillating movement of the yarn feeding point 4^c of the element 4^a. The longitudinal distance traveled by the yarn feeding point 4^c, is greater than that traveled by the traverse bar 11. As the layers of yarn build up on the tube 5, the element 4^a is urged away from the tube 5 because of the increasing diameter of the yarn package. This movement of the element 4^a causes the longitudinal travel of the thread delivery point 4^c of the element 4^a, to become progressively less as the diameter of the package becomes progressively greater. This results in the formation of tapered ends on the yarn package.

When it is desired to produce a yarn package having straight ends, instead of tapered ends, this can be accomplished by adjusting the plate 12, so that the cam slot 15 thereof is parallel with the traverse rail 11, thereby causing the oscillating movement of the element 4^a to remain the same in length or extent throughout the entire yarn winding operation.

When the yarn Y breaks, the yarn package is moved out of contact with the driving drum 6, and the guide arm 4^b is manually moved by the operator to its inoperative, or horizontal rest position B. The length of the guide arm 4^b is such that when this arm is moved to its horizontal inactive position B, the center point of the aperture or eye E, of the device 4^a, will be on a line C representing the central dividing line of the reciprocating stroke length of the device 4^a when in its position B. Assuming that the cam plate 12 has been fixed in selected inclined relation to the traverse rail 11, as shown in Fig. 2, then the yarn guide aperture or eye E, will only carry out a slight or limited movement toward and away from the yarn package, along the straight line C (see Fig. 2) which centrally divides the maximum reciprocating stroke length or any part of the device 4 while in its inactive position B. When the cam plate 12 is fixed in selected position so that the cam slot 15 is parallel with the traverse rail 11, to effect production of straight end yarn packages, the guide member 4^b will remain parallel with the center line C maintaining the full traverse stroke in the operative or inoperative position. This, of course, will make the threading operation more difficult when the traverse rail 11 travels at rapid speed.

It is to be particularly noted that the cam plate 12 may be selectively adjusted and fixed in position, so that the cam slot 15 is either inclined with respect to the traverse rail 11 to produce tapered end yarn packages, or in such manner that the cam slot 15 is parallel to the traverse rail 11 to produce straight end yarn packages. When fixed in the first of said mentioned positions, the yarn guide eye E will limitedly move along the center line C during the time that the

guide arm 4^b is in its horizontal or inactive position B and the machine is in operation. The extent of such movement carried out by the eye E depends upon the angular relation of the cam slot 15 with respect to the traverse rail 11.

After the tube 5 is supplied with a measured quantity of yarn, the usual automatic means provided in such machines, functions to move the completed yarn package out of contact with the driving drum 6. The operator then moves the guide arm 4^b to its horizontal or inoperative position B and substitutes an empty tube 5 for the completed yarn package while the machine is in operation. When this involves rethreading of the element 4^a, the procedure followed is the same as above explained.

Of course, the novel yarn delivery guide means shown and described, can be changed and modified in various ways without departing from the invention herein disclosed and more particularly defined by the hereto appended claims.

I claim:

1. In a textile apparatus of the character described, the combination with a yarn receiving bobbin, means for rotating the bobbin, a traverse bar, and a unit including a pivotally connected yarn delivery arm provided with a yarn guide aperture at the free end thereof; of means mounting the unit on the traverse bar so that the yarn delivery arm is freely movable to project from one side or the other of said traverse bar to a plurality of selective locations and unobstructed positions of the yarn guide aperture substantially equi-distant from said traverse bar during operation of the apparatus including an active location relative to the bobbin where the yarn guide aperture is adjacent the bobbin surface and travels therealong and an inactive location where the yarn guide aperture is unobstructedly held in a substantially motionless rethreading position during the movement of the traverse bar.
2. In a textile apparatus of the character described, the combination with a yarn receiving bobbin, means for rotating the bobbin, a traverse bar, and a unit including a pivotally connected yarn delivery arm provided with a yarn guide aperture at the free end thereof; of means mounting the unit on the traverse bar so that the yarn delivery arm is freely movable to project from one side or the other of said traverse bar to a plurality of selective locations and unobstructed positions of the yarn guide aperture substantially equi-distant from said traverse bar during operation of the apparatus including an active location relative to the bobbin where the yarn guide aperture is adjacent the bobbin surface and travels therealong and an inactive location where the yarn guide aperture is unobstructedly held in a substantially motionless rethreading position, and means for imparting an arcuate movement to the yarn delivery arm when the yarn guide aperture is in its said active location.
3. In a textile apparatus of the character described, the combination with a yarn receiving bobbin, a traverse bar and means for rotating the bobbin; of a reciprocating yarn delivery guide device provided with a yarn guide aperture, pivot means supporting said yarn delivery device on said traverse bar for arcuate movement of said yarn delivery guide device during operation of the apparatus from an active location of reciprocation where the yarn guide aperture is in yarn feeding position adjacent said bobbin to an inactive location providing a predetermined fixed rethreading position for the yarn guide aperture,

and means including a stationary cam element for maintaining the yarn guide aperture of said device on the center line dividing the reciprocating stroke length of the device while the latter is in its inactive location of reciprocation.

4. In a textile apparatus of the character described, the combination with a yarn receiving bobbin, a traverse bar and means for rotating the bobbin; of a reciprocating yarn delivery guide device provided with a yarn guide aperture, pivot means connecting said yarn delivery device to said traverse bar for arcuate movement of said yarn delivery guide device during operation of the apparatus, to project from one side of the traverse bar to the other and position the yarn guide aperture substantially equidistantly spaced from the traverse bar from an active location of reciprocation where the yarn guide aperture is in yarn feeding position adjacent said bobbin on one side of the traverse bar to an inactive location providing an unobstructed predetermined fixed rethreading position for the yarn guide aperture on the other side of the traverse bar, and means including a stationary cam element and a co-operatively arranged cam roller on said device for maintaining the yarn guide aperture of the latter on the center line dividing the reciprocating stroke length of the device during movement of said yarn delivery device by said traverse bar.

5. In a textile apparatus of the character described, the combination with a yarn receiving bobbin and means for rotating the bobbin; of a yarn delivery guide device provided with a yarn aperture, a reciprocatively operated traverse rail, pivot means mounting said device on said traverse rail for reciprocation therewith and independent movement thereof, from an active position of reciprocation where the yarn guide aperture projects from one side of the traverse bar and is in yarn feeding position adjacent said bobbin to project from the other side of the traverse bar, an inactive position providing a predetermined fixed and unobstructed rethreading position for the yarn guide aperture during operation of the apparatus, of a freely rotatable cam roller secured to said yarn delivery guide device, and a stationary cam element arranged to effect actuation of said cam roller during reciprocation of the traverse rail so as to limitedly move the yarn guide aperture of said device along the center line dividing the reciprocating stroke length of the device while in its inactive location of reciprocation.

6. In a textile apparatus of the character described, the combination with a yarn receiving bobbin, means for rotating the bobbin; of a yarn delivery guide device provided with a yarn guide aperture, a reciprocatively operated traverse rail, pivot means mounting said device on said traverse rail for reciprocation therewith and independent movement thereof from an active position of reciprocation where the yarn guide aperture is in yarn feeding position adjacent said bobbin on one side of said traverse bar to an inactive equi-distant position on the other side of said traverse bar providing a predetermined fixed and unobstructed rethreading position for the yarn guide aperture during operation of the apparatus, of a freely rotatable cam roller secured to said yarn delivery guide device, and a stationary cam element arranged to effect actuation of said cam roller during reciprocation of the traverse rail so as to maintain the yarn guide aperture of said device substantially motionless lat-

erally while the yarn guide aperture is in its unobstructed and fixed inactive position.

7. In a textile apparatus of the character described, the combination with a yarn receiving bobbin, means for rotating the bobbin; of a yarn delivery guide device provided with a yarn guide aperture, a reciprocatively operated traverse rail, pivot means mounting said device on said traverse rail for reciprocation therewith and independent movement thereof from an active position of reciprocation where the yarn guide aperture is in yarn feeding position adjacent said bobbin to an inactive position providing an unobstructed predetermined substantially motionless rethreading position for the yarn guide aperture in a lateral direction, of a freely rotatable cam roller secured to said yarn delivery guide device, and a stationary cam element which is adjustably mounted for selective positioning to effect actuation of said cam roller during reciprocation of the traverse rail so as to maintain the yarn guide aperture of said device in the substantially motionless unobstructed location while the latter is in its inactive position with variable active movements of the yarn guide aperture in the active position of said yarn guide delivery device.

8. In a textile apparatus of the character described, the combination with a yarn receiving bobbin, means for rotating said bobbin and a reciprocating traverse bar; of a normally fixed cam, a bracket pivotally supported on said reciprocating traverse bar; of a normally fixed cam, a bracket pivotally supported on said reciprocating traverse bar for swinging movement in the plane of reciprocation of the latter, a cam roller carried by said bracket so as to move therewith and said reciprocating traverse bar in constant engagement with said cam to thereby cause swinging movement of said bracket during its reciprocation with said traverse bar, and a yarn guide arm pivotally mounted on said bracket for arcuate movement toward and away from said bobbin.

9. In a textile apparatus of the character described, the combination with a yarn receiving bobbin, means for rotating said bobbin and a reciprocating traverse bar; of a normally fixed cam, a bracket pivotally supported on said reciprocating traverse bar for swinging movement in the plane of reciprocation of the latter, a roller carried by said bracket to as to move therewith and said reciprocating traverse bar in constant engagement with said cam to thereby cause swinging movement of said bracket during its reciprocation with said traverse bar, a yarn guide arm having a yarn guide aperture at its free end, means pivotally connecting said yarn guide arm and bracket so as to enable selective swinging movement of the yarn guide arm from an active position projecting to one side of the traverse bar to an inactive position projecting to the other side of the traverse bar thereby bringing the yarn guide aperture of said arm from a selective position on one side of said traverse bar to another selective position on the other side of said traverse bar during reciprocation of the latter and while the said cam roller is in constant engagement with said normally stationary cam.

10. In a textile apparatus of the character described, the combination with a yarn receiving bobbin, means for rotating said bobbin and a reciprocating traverse bar; of a normally fixed cam adjacent said traverse bar, a bracket pivotally supported on said traverse bar so as to bodily

move therewith in operative engagement with said cam so as to cause swinging movement of said bracket in the plane of reciprocation of said traverse bar during reciprocation of the latter, a yarn guide arm having a yarn guide aperture at its free end, means pivotally connecting said yarn guide arm and bracket for positioning of the yarn guide arm to project to one side of said traverse bar for movement of the yarn guide aperture parallel to the reciprocating motion of said traverse bar and positioning of the yarn guide arm to project to the opposite side of the traverse bar for unobstructed limited movement of the yarn guide aperture substantially at right angles to said traverse bar.
